UNITED STATES PATENT OFFICE.

ARTHUR O. AUSTIN, OF BARBERTON, OHIO, ASSIGNEE, BY MESNE ASSIGNMENTS, TO THE OHIO BRASS COMPANY, OF MANSFIELD, OHIO, A CORPORATION OF NEW JERSEY.

INSULATED CONTROL.

Application filed August 11, 1924. Serial No. 731,509.

This invention relates to means for controlling the discharge from electrodes connected with the dielectric members of insulators in order to permit higher voltages to be impressed on the insulators without producing flash-over.

The invention is exemplified in the combination and arrangement of parts shown in the accompanying drawings and described in the following specification, and it is more particularly pointed out in the appending claims.

In the drawings—

Fig. 1 is an elevation with parts in section showing an insulator having one embodiment of the present invention.

Fig. 2 is a top plan view of the insulator shown in Fig. 1.

Figs. 3, 4, 5 and 6 are top plan views of insulators showing modified forms of the invention.

Fig. 7 is a section on line 7—7 of Fig. 5.

Figs. 8 and 9 are plan and elevation respectively of an insulator showing a modified form of the invention.

Figs. 10, 11, and 12 are sections on lines 10—10, 11—11 and 12—12 respectively of Fig. 8.

In forming insulated controls used to raise or prevent the flash-over of insulators, the device may be readily made when attached separately to a pin type or suspension insulator. When made as a part of the insulator itself, however, the construction is more difficult. In many cases an insulated control such as disclosed in my prior Patent No. 1,521,743, January 6, 1925, while giving very fine results may be expensive or inconvenient to install and a less expensive method of producing results may be desired.

In the case of bus insulators as well as pin types and suspension types, there may be a strong tendency to discharge from the cap along the upper surface. If an annular ring is raised, it is ordinarily necessary to cover this with a water shed or to fill the resulting depression with some suitable compound so that water will not freeze and destroy the insulator. This damage due to freezing increases the cost of the insulator and unless the necessary protective measures are carefully carried out may create a hazard, particularly in localities where there is rain likely to be followed by freezing.

Fig. 1 shows a bus insulator equipped with

a draining type of insulated control which may be applied directly to the upper weather surface of a pin or suspension insulator. While the method is particularly applicable to bus insulators, it may be used in many types of pin insulators as well as suspension insulators. Fig. 1 shows the adaption of the method to a bus or switch insulator. In Fig. 1 the insulating elements or members 10, 11 and 12 are shown in half section half elevation. The insulator is mounted on a pin 13 and has a cap 14 cemented to its head. Under electrical stress the discharge tends to start from the lower edge of the cap at the point 15. This discharge is partly caused by the high stress and the charging current of the member 10. If, however, an insulating ring or barrier 16 is raised from the surface, this charging current will tend to be arrested and the voltage can be raised until discharge will take place from some other point higher up on the cap or will be forced over the barrier thereby increasing the voltage which may be carried without causing flash-over. The barriers on the upper side not only tend to prevent an accumulative discharge out over the flange which may greatly lower the flash-over of the insulator, particularly under high frequency surges, but the length of leakage path is increased as well as the surface resistance. The streamers in the groove act as conductors and tend to screen the other portions in their vicinity so that the voltage may be raised without causing discharge. It is evident, however, that water will be trapped in the groove unless openings are provided at or near the low point or unless the insulator is in an approximately horizontal position in which case no provision is necessary. If a groove or notch is cut in the barrier 16, a streamer starting from the lower edge of the cap at 15 may discharge through this opening or groove and the performance of the insulator will not be appreciably improved and may possibly be poorer in some cases. By making the groove, however, in a tangential or spiral direction and close to a charged surface, it is possible to utilize the principle of the insulated control and prevent discharge along the groove.

While the length of the groove is a factor, it is not nearly as important as the mutual effect of a charged surface at the same or slightly higher voltage, which tends to suppress the streamer in the groove. The proximity of

the groove to the charged surface maintains a potential throughout the groove approximating the potential of the charged surface so that there is no considerable drop in potential along the groove. Since the surface resistance along the groove is high and the potential drop relatively low due to the proximity of the charged surface the current in the groove will be kept down.

10 One arrangement is clearly shown in Fig. 2 which is the plan view of the upper face of the insulator shown in Fig. 1. A streamer starting from the edge of the cap 14 will tend to flow along the groove 17. As this groove, 15 however, is very close to the inside of the barrier adjacent to the cap, the charging current will be largely supplied from the cap or conducting streamers on the inside of the barrier so that there will be a strong tendency 20 to repress the streamer tending to flow out the groove 17. It is the suppression of the streamer that is desired. In order that this be accomplished, to the best advantage, it is necessary to make the path of discharge close 25 to a charged surface or one which is adjacent to the electrode or conducting surface. Owing to this principle, it is possible to obtain the benefit of an insulated control making same integral with the part of the insulator, and, at the same time forming an insulator which will not trap water. There are a number of ways of accomplishing the result. The general principle, however, remains the same in that the path of discharge 30 through a draining slot or opening is approximately parallel or close to a charged surface or recess which is drained.

Fig. 3 shows another form. In this case the groove 16 is drained by a hole 18 which 40 runs close to the groove 16 and is connected to the groove 16 at its inner end.

Fig. 4 shows another modification which is very similar to that in Fig. 1 but shows a somewhat different contour of di-electric 45 ribs. The ribs 16 in this case have a gradual outward inclination instead of somewhat abrupt offset portions as in Fig. 2.

In Fig. 5 there is provided a pair of concentric ribs or flanges 19 and 20 spaced from 50 one another and providing a channel 21 adjacent the cap 14 and a channel 22 concentric with the channel 21 but separate therefrom by the flange 19. In order to drain the channel 21 there is provided a plurality of 55 openings 23 distributed in spaced relation and extending through the base of the flange 19. Similar openings 24 are provided through the flange 20 for draining the channel 22 but the openings 24 are arranged in staggered 60 relation to the openings 23 so that these openings do not provide a continuous path for discharge streamers.

It will be apparent that a streamer passing through the opening 23 will be directed 65 along the channel 22 in close proximity to

the charged surface formed by the flange on the cap 14 but separated from this surface by the flange 19. The proximity of the charged flange and the streamers emanating therefrom to the channel 22 will tend to stop the flow of streamers in the channel 22.

In the construction shown in Fig. 6, a plurality of concentrically staggered baffle flanges or ribs 25 is provided, the baffles being beveled downwardly to the surface of the dielectric member at spaced positions throughout their length to provide drainage passages 26. These passages, as will be seen from the drawings, are arranged in staggered relation to one another so that the operation will be similar to the device shown in Fig. 5.

There are many ways in which an insulated control may be applied to the upper surface of an insulator and still drain water which may be entrapped between the insulating member and the conducting surface. It is essential, however, that the surface tending to discharge be covered with the insulating member and; furthermore, that the draining passage be screened with a charged surface or have a long path not directly in the line of normal discharge.

Fig. 8 shows a plan view of the top of the insulator shown in Fig. 9, the insulator being the same general type as that shown in Fig. 1. A discharge is prevented from the lower edge of the cap 14 by baffle 27, 28 and 29. One method of draining the enclosure is by an open slot 29'. Discharge along this is prevented by slots 30 adjacent to slot 29', the slots 30 being conducting in their lower portion, the conducting material being in electrical contact with the cap 14, either through direct connection or by discharge. The conducting slots 30 screen the slot 29' and unless the path 29 has a relatively low resistance, discharge will be prevented along this path.

Fig. 10 shows a cross section along the line 10—10 of Fig. 8. In some cases where it is desirable to screen the slot for a considerable distance, charged surfaces may be carried out to a point where there is danger of discharging from them. This may be prevented by the method shown in Fig. 11 which is a section on the line 11—11. In this case the charged screening surfaces 31, although open and in contact with the cap 14 at their inner surface, are closed at their outer end forming a closed insulated control on each side of the draining slot 32.

Fig. 12 is a section on the line 12—12 and shows another method of screening the discharge. Opening 33 is a hole in this instance. The discharge is prevented along the hole by a coated surface of cylindrical form extending part way around the discharge hole 33. This charged surface is shown by 34. It is not necessary that the charged or screening surfaces be in electrical contact with the cap or electrode if their arrangement is such that

they will become charged surfaces before discharge will take place through the slot or opening. In order to be most effective, however, it is generally advisable to place conducting material or coating in these surfaces to insure an efficient screening action.

I claim—

1. An insulator comprising a dielectric member, an electrode, and means providing 65 separate paths of discharge from said electrode, said paths being arranged adjacent one another so that the discharge along one path will be diminished by the influence of the discharge in an adjacent path.
- 10 2. An insulator comprising a dielectric member, an electrode, and means for providing a plurality of paths of discharge from said electrode, said paths being insulated from one another while the portion of one 70 path more removed from said electrode is arranged closely adjacent the portion of another path closer to said electrode.
- 15 3. An insulator comprising a dielectric member, an electrode, and means providing 75 a plurality of discharge paths from said electrode, remote portions of each of said paths being arranged closely adjacent a portion of another path closer to said electrode, the adjacent portions of said paths being separated 80 from one another by a dielectric barrier.
- 20 4. An insulator comprising an electrode, a dielectric member connected with said electrode and having a surface thereof extending 85 away from said electrode and barriers of dielectric material formed on said surface to provide restricted paths of discharge from said electrode, said paths having open end portions and having portions thereof between said electrode and open end portions subjected to the influence of a high potential for 90 diminishing discharge through said open end portions, said electrode being arranged to extend into the space at the sides of said barriers.
- 25 45 5. An insulator comprising an electrode, a dielectric member connected with said electrode and having a surface extending away 95 from said electrode and means on said surface providing a plurality of restricted paths 100 of discharge from said electrode, said paths having drainage openings and having portions thereof between said drainage openings and said electrode arranged in close proximity to said electrode but separated therefrom by dielectric material, said electrode being arranged to extend into position adjacent 105 open ends of said paths.
- 30 6. An insulator comprising an electrode, a dielectric member connected with said electrode and having a surface extending therefrom and means on said surface providing a 110 plurality of paths of discharge from said electrode, said paths having drainage openings and each path having a portion thereof 115 between said electrode and its drainage opening arranged adjacent a portion of another path closer to said electrode, the adjacent portion of said paths being separated by dielectric material, said electrode being arranged to extend into position adjacent open ends 120 of said paths.
- 35 7. An insulator comprising an electrode, a dielectric member connected with said electrode and having a surface extending therefrom and ribs on said surface forming paths 125 for discharge from said electrode, there being drainage openings at the lowermost portions of said paths while portions thereof closer to said electrode are disposed closely adjacent to said electrode but separated therefrom by dielectric material, said paths having open end portions directly adjacent said electrode and not separated from said electrode by dielectric material.
- 40 8. An insulator comprising an electrode, a dielectric member connected with said electrode and having the upper surface thereof extending laterally from said electrode and ribs on said surface arranged to form separate over-lapping paths of discharge from 130 said electrode, the lowermost portions of said paths being open to provide drainage.
- 45 9. An insulator comprising an electrode, a dielectric member connected with said electrode and having a surface extending therefrom and a plurality of spirally arranged 135 ribs on said surface, said ribs being arranged in over-lapping relation to provide a plurality of paths of discharge from said electrode which over-lap one another while permitting drainage at the outer ends of the paths formed by said ribs.
- 50 10. An insulator having a charged fitting, a dielectric barrier for preventing discharge from said fitting, there being a drainage passage through said barrier, said fitting forming a charged surface adjacent said passage but insulated therefrom, the inner end of said 140 passage being open adjacent said fitting.
- 55 11. An insulator having a dielectric barrier thereon provided with a drainage passage, said passage being shielded by a charged surface, one end of said passage being open adjacent said surface and having direct connection therewith.
- 60 12. An insulator having a fitting connected therewith, a dielectric barrier for restricting discharge from said fitting, said barrier having a drainage passage therethrough, said 145 passage being shielded by a charged surface separated from said passage by dielectric material, said drainage passage being open directly adjacent said fitting and communicating directly with said fitting.

In testimony whereof I have signed my name to this specification on this 6th day of August, A. D. 1924.

ARTHUR O. AUSTIN.
